UNITED STATES PATENT OFFICE

2,463,524

ELECTRON DISCHARGE DEVICE

Palmer P. Derby, Boston, Mass., assignor to Raytheon Manufacturing Company, Newton, Mass., a corporation of Delaware

Application March 10, 1945, Serial No. 582,046

8 Claims. (Cl. 315—5)

1

This invention relates to a magnetron microwave oscillator.

An object of this invention is to produce such an oscillator which can operate successfully with high power output and efficiency on continuous wave operation.

Another object is to devise such an oscillator in which the separation between the principal mode and the closest adjacent mode is greater than a critical value below which successful continuous wave operation does not occur.

A further object is to devise such a magnetron in which the cathode structure is arranged to conduct away large amounts of heat generated at the cathode during continuous wave operation, said conduction to occur at a rate sufficient to prevent the overheating of the cathode.

The foregoing and other objects of this invention will be best understood from the following description of an exemplification thereof, reference being had to the accompanying drawings wherein:

Fig. 1 is a vertical section through one form of my invention;

Fig. 2 is a horizontal section taken along line 2—2 of Fig. 1;

Fig. 3 is a broken-away perspective view showing two of the anode paddles; and

Fig. 4 is a set of curves showing in a qualitative manner certain relationships within the magnetron which may be taken into consideration in embodying the principles of my invention in a practical device.

The magnetron illustrated in Figs. 1-3 comprises a tubular anode structure 1 made of a cylinder of conducting material, such as copper. A plurality of radially-disposed plates 2 likewise formed of conducting material, such as copper, are soldered in place along the inner surface of the hollow cylinder 1. Each pair of plates, together with the intervening portion of the cylinder 1, define a cavity resonator. The inner ends of the radial plates are adapted to serve as anode faces for receiving electrons emitted from the centrally-disposed cathode 3. Alternate plates 2 are electrically connected by means of conducting straps 4, 5, 6 and 7. The straps 4 and 5 are located at one end of the anode structure, the strap 4 being electrically connected to alternate plates 2 and the strap 5 connected to the intervening alternate plates. At the other end of the anode structure, the strap 6 is connected to those plates to which the strap 5 is connected, and the strap 7 is connected to those plates to which the strap 4 is connected. Such

a strap arrangement substantially decreases the tendency for the device to operate in various spurious modes. It is particularly effective in suppressing the higher modes above the principal mode.

The energy developed within the cavity resonators is led out from the device by means of a coupling loop 8 extending into one of the cavity resonators. One end of the loop 8 is connected to the inner end of a pipe 9 hermetically sealed in the wall of the envelope 1. The other end of the loop 8 is connected to a conductor 8' which extends through a glass seal 10 hermetically sealed in the outer end of the pipe 9. An additional hollow conductor, not shown, may be connected to the pipe 9 so as to surround the conductor 8', forming therewith a concentric transmission line through which the energy generated by the oscillator may be fed.

20 The upper and lower ends of the cylinder 1 are closed by the upper and lower caps 11 and 12 formed of a suitable conducting material, such as copper, and hermetically soldered into the ends of the cylinder 1. The upper cap 11 is provided with a central opening into which a magnetic pole piece 13 is hermetically soldered so as to close said opening. Similarly the lower cap 12 is provided with a central opening in which is hermetically soldered a lower pole piece 14. The pole pieces 13 and 14 are formed of highly permeable iron. Any suitable form of external magnet may be applied to these pole pieces so as to impart opposite polarities thereto, whereupon the proper magnetic field is set up within the magnetron about the cathode 3.

35 The cathode 3 is formed with a central tubular section 15, the outer surface of which is coated with firmly adherent electron-emitting oxides. Connected to the upper and lower ends, respectively, of the central section 15 are enlarged hollow end sections 16 and 17. The entire assembly 15, 16 and 17 may be made of a suitable metal, such as nickel. A heating coil 18 is supported within the section 15. One end 19 of the coil 40 18 is welded within and to the hollow section 16, and the lower end 20 extends through and beyond the lower section 17. The lower end 20 of the heater is in turn welded to a lead-in conductor 21. The pole pieces 13 and 14 are provided, 45 respectively, with bores 22 and 23, into which are received the enlarged end sections 16 and 17 of the cathode 3. The end section 17 is provided with a reduced extension 24 which fits into the upper end of a hollow rod 25 made of a highly 50 conductive material, such as copper. The rod

25 has hermetically soldered to its outer surface a cup 26 of a suitable metal which seals readily to glass. To the upper portion of this cup is sealed a glass sleeve 27, the upper end of which is in turn sealed to the ring 28 of similar sealing metal, which is in turn hermetically soldered within an enlargement formed in the lower end of the pole piece 14. The lead-in conductor 21 extends out through a glass bead 29 sealed in the lower end of a metal tube 30, which in turn is soldered in the lower end of the hollow rod 25. Supported on the outside of the lower end of said rod 25 is a heat radiator 32 provided with a plurality of heat-radiating fins 33.

When a magnetron of the type as described herein is operated on continuous wave, a very considerable amount of heat is fed back into the cathode by electronic discharge occurring between the cathode and the anode. In order for such operation to be successful, this heat must be conducted away from the emitting portion of the cathode at a sufficient rate to prevent overheating of the cathode. The arrangement which I have described above accomplishes this result. It will be noted that the end sections 16 and 17 of the cathode consist of relatively massive metal bodies having a high heat conductivity and a relatively high heat capacity as compared with the emitting section 15. Also the end sections 16 and 17 extend for a considerable distance within the massive metal bodies provided by the pole pieces 13 and 14. Heat is thus readily radiated from the end sections 16 and 17 to the massive bodies 13 and 14 from which the heat may be conducted very rapidly. If desired the bores 22 and 23 within the pole pieces 13 and 14 may be provided with black surfaces so as to more readily absorb the energy radiated from the end sections 16 and 17. Also the lower section 17 is in intimate contact with the highly conducting rod 25 so that in addition to the radiation the heat is led away from the end section 17 by conduction through the rod 25. The heat radiator 32 forms an excellent means for dissipating this heat. In some instances it may be desired to blow air against the heat radiator 32 to conduct the heat away more rapidly.

I have found that with such a construction, extraordinary amounts of power may be delivered by the tube as a continuous wave oscillator without overheating the cathode.

Even if a magnetron is constructed so that the heat is conducted away from the cathode with sufficient rapidity to prevent overheating, nevertheless successful continuous wave operation of the magnetron may not be secured unless additional features are incorporated in the tube. For effective continuous wave operation, the magnetron should be operated with a relatively high ratio between the voltage between the anode and cathode and the average current flow between the anode and cathode. I have found that a ratio of the order of 1,000 volts/amp. or greater is desirable. This is a dynamic ratio and not a static one. The ratio represents the change in anode voltage required to produce a desired change in anode current. However, when an attempt is made to operate prior types of micro-wave magnetrons on continuous wave, the tube tends to oscillate at various frequencies other than the desired frequency, and therefore is substantially inoperative for continuous wave purposes. I have found that this defect can be eliminated if the percentage mode separation in the magnetron is made greater than a critical value, depending on the mode index number.

In a magnetron, the mode index number is an expression of the number of voltage maxima points which exist throughout the tube structure during the generation of oscillations. In a multiple anode multiple cavity resonator type magnetron, such as that illustrated herein, it is desirable to concentrate the oscillations produced in the principal mode in which successive anode electron-receiving faces are of opposite voltage phase. If N represents the number of anode plates 2 within the tube, and n represents the index number of the principal mode, then

$$n = \frac{N}{2} \quad (\text{Equation 1})$$

In a magnetron such as I have been discussing above, the percentage mode separation between the principal mode and the next lower mode is

$$\frac{\lambda_n - \lambda_{n-1}}{\lambda_n} \quad (\text{Equation 2})$$

where λ_n is the wave length of the principal mode and λ_{n-1} is the wave length of the next lower index number mode at which the tube structure has a substantial tendency to oscillate. Likewise the percentage mode separation between the principal mode and the next higher mode is

$$\frac{\lambda_{n+1} - \lambda_n}{\lambda_n} \quad (\text{Equation 3})$$

where λ_{n+1} is the wave length of the next higher index number mode at which the tube structure has a substantial tendency to oscillate.

A general expression of percentage mode separation may be given as

$$\frac{|\lambda_n - \lambda_a|}{\lambda_n} \quad (\text{Equation 4})$$

where λ_a is the wave length of the mode of either higher or lower index number which is closest to the principal mode and

$|-|$

is the well-known symbol for the absolute magnitude of the difference between two quantities.

I have found that for successful continuous wave operation, the percentage mode separation must be greater than a critical value which is equal to

$$\frac{1}{n+1} \text{ or } \frac{1}{\frac{N}{2}+1} \quad (\text{Equation 5})$$

Under these conditions the possible modes of oscillation other than the principal mode are sufficiently removed from the principal mode to be substantially suppressed, and the principal mode is permitted to be excited to a marked degree. At mode separations of lesser percentage, other modes than the principal mode tend to be excited as the anode-cathode current increases from its zero value. This destroys the utility of the device as a continuous wave oscillator. In Fig. 4 I have plotted, by the solid curve, the critical percentage of mode separation against the number of anode arms.

From the foregoing it will be noted that as the number of anode arms increases, the permissible mode separation decreases so that by choosing a large number of anode arms, such as twenty or more, continuous wave operation might be obtained with a percentage mode separation of about 9.1% or less. However, the use of such a large number of anode arms introduces various difficulties so that I prefer to utilize a smaller number of anode arms, such as eighteen or less.

I have also found that if certain relationships are maintained in a tube, the desired critical mode separation may readily be reached and in most instances greatly exceeded. For all practical purposes the percentage mode separation must be substantially greater than the critical value, due to the following reasons. When a magnetron is set up with a certain magnetic field and the anode voltage is increased to a value at which the anode-cathode current begins to flow, the tube will start oscillating, and if the mode separation is greater than the critical value, these oscillations will be in the principal mode. However, if the mode separation is only slightly greater than the critical value, the anode-cathode current can be raised only a slight amount before additional modes are excited, thus rendering the tube unfit for continuous wave work. As the mode separation is increased beyond the critical value, the greater may be the increase or "excursion" of the anode-cathode current. It will be seen that the amount of power which such a tube can deliver is dependent on the magnitude of the anode-cathode current excursion. Thus in a practical tube the mode separation should be substantially greater than the critical value. Thus, for example, in a tube having sixteen anode arms, the critical percentage mode separation is about 11%. Yet for practical purposes I prefer to construct the tube with a percentage mode separation of the order of 50% or greater.

The factors which determine the percentage mode separation can be determined from the following empirical relationship which is approximately true for all practical configurations:

$$\omega^2 = \frac{1}{LC} \left[1 + \frac{2L}{A} \left(1 + \frac{1}{\frac{\omega^2 C_s A}{2 \sin^2 \theta} - \frac{A}{B} \cot^2 \theta - 1} \right) \right] \quad (\text{Equation 6})$$

where

$\omega = 2\pi f$; f being the frequency generated by the tube at the particular mode under consideration;

L =the total lumped inductance of one cavity resonator between two of the arms 2;

C =the total lumped capacity of said one cavity resonator. This includes the added capacity introduced into the resonator by the adjacent straps 4—7;

C_s =the capacity of the straps between the anode arms defining said one cavity resonator;

$$\theta = \frac{n'}{N} \pi$$

n' being the index number of the mode being considered.

$A=L_s+M_s$; L_s being the self-inductance of that part of one strap extending between the two anode arms of said one cavity and M_s being the mutual inductance between those portions of two adjacent straps which extend between said two anode arms; and

$$B=L_s-M_s.$$

The absolute magnitudes of C_s and A are usually made so small that the expression

$$\frac{\omega^2 C_s A}{2 \sin^2 \theta}$$

is a small value compared to unity. For the principal mode

$$\theta = \frac{\pi}{2}$$

and thus $\cot^2 \theta$ is zero. Under these conditions

the formula for the principal mode can be reduced substantially to the form

$$\omega^2 = \frac{1}{LC} \quad (\text{Equation 7})$$

The factors which vary as θ changes from the principal mode

$$\frac{\pi}{2}$$

to an adjacent mode

$$\frac{n-1}{N} \pi$$

or

$$\frac{n+1}{N} \pi$$

are

$$\frac{1}{\sin^2 \theta}$$

and $\tan^2 \theta$. As a matter of fact these factors have exactly the same value for the $n-1$ and $n+1$ modes so that for present purposes we need consider only the $n-1$ mode. In order to facilitate a determination of how these variable factors affect mode separation, I have plotted in Fig. 4 the values for

$$\frac{1}{\sin^2 \theta}$$

and $\cot^2 \theta$ for the $n-1$ mode for different numbers of anode arms. Since

$$\frac{1}{\sin^2 \theta} = 1 + \cot^2 \theta$$

by adjusting the scales as indicated, the same dotted curve may serve to indicate the values of both factors. It will be noted that the effect of the expression in Equation 6 containing

$$\frac{1}{\sin^2 \theta}$$

is opposite to that of the expression containing $\cot^2 \theta$ upon the mode separation. However, the proportionate effect of the

$$\frac{1}{\sin^2 \theta}$$

factor is less and also, as above indicated, the expression containing this is usually made so small as to be insignificant. Thus for most purposes we can consider only the effect of the expression containing $\cot^2 \theta$.

If we now select a value of ω for the next mode adjacent to the principal mode to satisfy the requirements for continuous wave operation described above, we can satisfy the requirements of Equation 6 by properly selecting the relative

proportions of L , C , C_s , L_s and M_s . We see, for example, that larger values of L will increase the mode separation. Therefore in my embodiment I have constructed my cavity resonators to have a relatively large cross-sectional area. Also if we make M_s larger and L_s smaller, the mode separation becomes larger. Thus it becomes desirable to place the straps 4 and 5, and 6 and 7, closely adjacent to each other to obtain a tight coupling between them.

If for some reason the mutual inductance of the straps cannot be made sufficiently large to give a large separation of modes, then the factor in Equation 6 containing

$$\frac{1}{\sin^2 \theta}$$

can be made to predominate and give the desired mode separation. This can be done by making the strap capacity C_s larger. Such large strap capacity may be obtained by increasing the areas

75 of the straps facing each other.

By the use of the term "strap" and "straps" in the specification and claims, I do not intend to be limited to the shape of the straps 4-7 as illustrated herein. Any cross-sectional shape for the conductors interconnecting the anode arms is included in these terms provided the values C_s , L_s and M_s are such as to give the mode separation as defined.

For purposes of clarity in the claims, Equation 6 for the two values λ_n and λ_a can be expressed as

$$\left(\frac{2\pi v}{\lambda_n}\right)^2 = \frac{1}{LC} \left[1 + \frac{2L}{L_s + M_s} \left(1 + \frac{1}{\left(\frac{2\pi v}{\lambda_n}\right)^2 C_s (L_s + M_s) - 1} \right) \right] \quad (\text{Equation 8})$$

and

$$\left(\frac{2\pi v}{\lambda_n}\right)^2 = \frac{1}{LC} \left[1 + \frac{2L}{L_s + M_s} \left(1 + \frac{1}{\left[\frac{2\pi v}{\lambda_a}\right]^2 C_s (L_s + M_s) - \frac{L_s + M_s}{L_s - M_s} \cot^2 \left[\frac{\frac{N}{2} - 1}{N} \pi \right] - 1} \right) \right] \quad (\text{Equation 9})$$

where v is the velocity of light.

If a tube is constructed to scale as illustrated in the drawings, then such a tube will have incorporated in it the principles of my invention and will operate successfully on continuous wave.

It is to be understood that this invention is not limited to the particular details as described above. Although the use of straps is an excellent way of securing the requisite mode separation, yet it is possible to build unstrapped magnetrons with mode separations which exceed the critical value of this invention. As long as such separation exceeds this critical value in the manner as described above, successful continuous wave operation can be secured. Many other equivalents will suggest themselves to those skilled in the art. It is accordingly desired that the appended claims be given a broad interpretation commensurate with the scope of the invention within the art.

What is claimed is:

1. A magnetron comprising a cathode, an anode structure surrounding said cathode and comprising a plurality of anode arms disposed about said cathode, each arm having an electron-receiving face, and each pair of adjacent arms, together with that portion of said anode structure lying therebetween, defining a cavity resonator, said magnetron having a percentage mode separation substantially greater than the critical value

$$\frac{1}{\frac{N}{2} + 1}$$

where N is the number of anode arms.

2. A magnetron comprising a cathode, an anode structure surrounding said cathode and comprising a plurality of anode arms disposed about said cathode, each arm having an electron-receiving face, and each pair of adjacent arms, together with that portion of said anode structure lying therebetween, defining a cavity resonator, alternate anode arms being directly interconnected by a strap, the intervening anode arms being directly interconnected by another strap, said magnetron having a percentage mode separation substantially greater than the critical value

$$\frac{1}{\frac{N}{2} + 1}$$

where N is the number of anode arms.

3. A magnetron comprising a cathode, an anode

70

$$\left(\frac{2\pi v}{\lambda_n}\right)^2 =$$

$$\frac{1}{LC} \left[1 + \frac{2L}{L_s + M_s} \left(1 + \frac{1}{\left(\frac{2\pi v}{\lambda_n}\right)^2 C_s (L_s + M_s) - 1} \right) \right]$$

8 structure surrounding said cathode and comprising a plurality of anode arms disposed about said cathode, each arm having an electron-receiving face, and each pair of adjacent arms, together with that portion of said anode structure lying therebetween, defining a cavity resonator, alternate anode arms being directly interconnected by a strap, the intervening anode arms being directly interconnected by another strap adjacent said first-mentioned strap, said magnetron hav-

25 ing a percentage mode separation substantially greater than the critical value

$$\frac{1}{\frac{N}{2} + 1}$$

where N is the number of anode arms.

4. A magnetron comprising a cathode, an anode structure surrounding said cathode and comprising a plurality of anode arms disposed about said cathode, each arm having an electron-receiving face, and each pair of adjacent arms constituting the side walls of a cavity resonator, alternate anode arms being directly interconnected by a strap, the intervening anode arms being directly interconnected by another strap, the ratio between the sum of the self-inductance of the portion of one of said straps between two of said anode arms and the mutual inductance between the portions of two of said straps between said two anode arms 45 and the difference between said self-inductance and said mutual inductance being large compared to the product.

$$\frac{\omega^2 C_s A}{2}$$

50 where $\omega = 2\pi f$, f being the frequency of the magnetron at the

$$\frac{N}{2} - 1$$

55 mode, N being the number of said anode arms, C_s = the capacity of the straps between two adjacent arms, and $A = L_s + M_s$, L_s being said self-inductance and M_s being said mutual inductance.

60 5. A magnetron comprising a cathode, an anode structure surrounding said cathode and comprising a plurality of anode arms disposed about said cathode, each arm having an electron-receiving face, and each pair of adjacent arms constituting the side walls of a cavity resonator, alternate anode arms being directly interconnected by a strap, the intervening anode arms being directly interconnected by another strap, L , C , L_s , C_s and M_s being related in the equations

$$\left(\frac{2\pi v}{\lambda_n}\right)^2 =$$

$$\frac{1}{LC} \left[1 + \frac{2L}{L_s + M_s} \left(1 + \frac{1}{\left(\frac{2\pi v}{\lambda_n}\right)^2 C_s (L_s + M_s) - 1} \right) \right]$$

75

and

$$\left(\frac{2\pi v}{\lambda_a}\right)^2 = \frac{1}{LC} \left[1 + \frac{2L}{L_s + M_s} \left(1 + \frac{1}{\frac{\left[\frac{2\pi v}{\lambda_a}\right]^2 C_s (L_s + M_s)}{2 \sin^2 \left[\frac{N-1}{2} \frac{\pi}{N}\right]} - \frac{L_s + M_s}{L_s - M_s} \cot^2 \left[\frac{N-1}{2} \frac{\pi}{N}\right] - 1} \right) \right]$$

so that

$$\frac{\lambda_n - \lambda_a}{\lambda_n}$$

is substantially greater than the critical value

$$\frac{1}{N+1}$$

the above symbols having the following values:

v =the velocity of light,

L =the inductance of one of said cavity resonators,

C =the capacity of one of said cavity resonators,

L_s =the self-inductance of one of said straps between two adjacent anode arms,

M_s =the mutual inductance between the straps between said two anode arms,

C_s =the capacity of said straps between said two anode arms,

λ_n =the wave length of the principal mode of said magnetron,

λ_a =the wave length of the mode of said magnetron closest to said principal mode, and

$|-|$ is the symbol for the absolute difference in the magnitude of two quantities.

6. A magnetron comprising a cathode, an anode structure surrounding said cathode and comprising a plurality of anode arms disposed about said cathode, each arm having an electron-receiving face, and each pair of adjacent arms constituting the side walls of a cavity resonator, said cathode comprising a central electron emitting portion of relatively low heat capacity, end sections of metal and of relatively high heat capacity connected to the ends of said central portion and in good heat conducting relation therewith, two pole pieces supported at opposite ends of said anode structure, said pole pieces being of magnetic material and of relatively massive size relative to said end sections, said pole pieces being provided with elongated bores, said end sections projecting into said bores, each for a substantial distance.

7. A magnetron comprising a cathode, an anode structure surrounding said cathode and comprising a plurality of anode arms disposed about said cathode, each arm having an electron-receiving face, and each pair of adjacent arms constituting the side walls of a cavity resonator, said cathode comprising a central electron emitting portion of

relatively low heat capacity, an end section of metal and of relatively high heat capacity connected to one end of said central portion and in good heat conducting relation therewith, a pole piece supported at one end of said anode structure, said pole piece being of magnetic material and of relatively massive size relative to said end section, said pole piece being provided with an elongated bore, said end section projecting into said bore for a substantial distance, the opposite end of said central portion being in good heat conducting relation with a highly heat conductive rod, said rod extending exteriorly of said anode structure and carrying a heat radiator.

8. A magnetron comprising a cathode, an anode structure surrounding said cathode and comprising a plurality of anode arms disposed about said cathode, each arm having an electron-receiving face, and each pair of adjacent arms constituting the side walls of a cavity resonator, said cathode comprising a central electron emitting portion of relatively low heat capacity, end sections of metal and of relatively high heat capacity connected to the ends of said central portion and in good heat conducting relation therewith, two pole pieces supported at opposite ends of said anode structure, said pole pieces being of magnetic material and of relatively massive size relative to said end sections, said pole pieces being provided with elongated bores, said end sections projecting into said bores, each for a substantial distance, one of said end sections being in good heat conducting relation with a highly heat conductive rod, said rod extending exteriorly of said anode structure and carrying a heat radiator.
